UNITED STATES PATENT OFFICE

CHARLES MUELLER, OF NEW BRITAIN, CONNECTICUT.

PROCESS OF ETCHING METAL.

SPECIFICATION forming part of Letters Patent No. 660,262, dated October 23, 1900.

Application filed July 27, 1900. Serial No. 24,970. (No specimens.)

To all whom it may concern:

Be it known that I, CHARLES MUELLER, a citizen of the United States, residing in New Britain, in the county of Hartford and State of Connecticut, have invented certain new and useful Improvements in Processes of Etching Metal, of which the following is a specification.

This invention relates to processes of etching designs in metal; and one object of the invention is to provide an improved process of this character by means of which various metals may be quickly and inexpensively provided with designs or trade-marks, the present improved process being particularly adapted for use in applying trade-marks to cutlery.

A further object of the invention is to provide an improved process of this character in which the production of superior designs or trade-marks in metal is obtained with a great deal less skill and care than have heretofore been necessary, while at the same time a deep, particularly clear, and durable design is obtained, so that the metal can be properly polished or burnished without appreciably affecting the quality of the design.

In the present instance this improved process is exemplified in the drawings in connection with cutlery, although it is understood that it is applicable to all materials which can be etched by acid and is therefore not to be limited to such class of articles.

In the drawings accompanying and forming part of this specification, Figures 1, 3, 5, 7, 9, 35 and 11 illustrate the blade of a knife treated successively by the various successive steps of this improved process, while Figs. 2, 4, 6, 8, 10, and 12 are sectional views taken in lines *a a*, respectively, of said first-mentioned figures.

Similar characters of reference indicate corresponding parts in the different figures of the drawings.

The present improved process consists in a general way in applying to the article to be ornamented, which may consist of any material which can be etched with acid, a thin ground or first coat of a suitable varnish adapted to receive and hold the design, which is applied thereto by the use of an alkali solution or composition printed or stamped thereon by some suitable instrumentality. A sec-

ond varnish highly resistant to acids is then flowed over the article to protect all parts thereof except the design, which is then washed out in some suitable way, and the bared metal corresponding with the design is then subjected to a suitable acid to etch the same.

I am aware that it is not new to apply a ground coat of gum-guaiac varnish to the metal to be ornamented, then printing on such ground coat by a potash or soda composition the design to be etched, and then etching such ornamentation by the application of an acid; but by practical experience with this process I am also aware that it has many disadvantages. In such old process the gum-guaiac varnish not only acts as the material to receive the imprint of the design, but also as a resist for the acid, so as to protect the metal around the design during the application of the etching material, and as it is not a superior acid-resisting material consequently this process is unsatisfactory for some cutlers and absolutely of no use for others, since in the first place the gum-guaiac varnish must be applied with great care, for if it is in the least heavy the alkali print will not penetrate to the metal so as to allow the acid to bite into such metal. If, however, the varnish is laid on not quite heavy enough, the result is also disastrous, since the varnish will not resist the acid sufficiently long to prevent such acid from eating the metal around the design. Furthermore, another difficulty arises on account of the temperature. In damp weather a gum-guaiac varnish will dry cloudy and leave many small holes around the stamp or design as the result. In rainy weather or damp days the alkali solution will draw water, and on that account will print in blotted lines, so that this process could not be used at all on many days of the year on account of its many disadvantages. By my improved process all of these disadvantages are done away with, so that I am enabled to use the same at all times of the year regardless of the weather and also with considerably less care and skill than have heretofore been found necessary.

This improved process consists in first coating the article to be ornamented, in the present instance shown as a knife-blade 2, with a suitable base coat or layer of material or var-

nish, and for this purpose I have found that a varnish composed of gum-guaiac and alcohol is preferable, when a suitable antidrier—such, for instance, as fusel-oil—is mixed therewith. A very thin coating 3, Figs. 1 and 2, of this composition is applied to the knife-blade. By the use of a very thin layer of this varnish fine hair-line prints can be made with a much smaller percentage of the alkali printing solution, thus doing away with the tendency to blot the lines and characters in damp weather. Without the addition of an antidrier—such, for instance, as fusel-oil—however, I have found that it is not practicable to use a thin coat of gum-guaiac varnish, since this thin coat quickly dries and leaves after drying only a powder instead of a varnish, to which, of course, the second varnish which I apply and which acts as a resist to the acid solution would not stick. By the incorporation of fusel-oil with the varnish the drying thereof is delayed, so that a thin coating of this varnish can be applied to the article and will remain thereon in a thin continuous film. On this first coating 3 is then printed or stamped the ornamentation or design to be etched, shown herein as a trade-mark 4, Figs. 3 and 4, by means of a suitable alkali, such as a potash solution or composition, applied by means of a suitable printing instrumentality—such, for instance, as rubber or flexible type or plates. This alkali printing composition applied to the gum-guaiac varnish combines therewith, the chemical action of such alkali solution and the gum-guaiac varnish having the fusel-oil therein being such that the design can be washed out in some suitable manner, as by the use of water, at the proper time, thereby to bare the metal and permit the acid to bite thereinto. Owing to the many disadvantages which are present when gum-guaiac varnish is used as an acid-resist I flow over the metal a second material or varnish of such a composition that it will dry in a smooth continuous layer 5, Figs. 5 and 6. This second varnish not only acts as an acid-resist to more thoroughly protect all parts of the article previously covered by the gum-guaiac varnish, but also protects any part of the article not so covered, so that should the gum-guaiac varnish dry in an imperfect condition, or with holes therein, owing to the weather or other causes, the second varnish will thoroughly protect the metal from the acid. This second varnish, which acts as the acid-resisting layer, preferably comprises bitumen, rosin, and balsam-fir dissolved in turpentine and benzol. This forms a composition which not only resists the acid, which may be used of double the ordinary strength as compared with that which it has heretofore been possible to use with a guaiac varnish constituting the protection for the metal, but it is also proof against the water which may be employed for washing out the design. This composition is flowed over the varnish-

covered portions of the metal and the design, but recedes from the design and forms a wall 6, Fig. 6, around the same, whereupon such design may be washed out, Figs. 7 and 8, in some suitable manner, as by the use of water applied, if desired, by means of a camel's-hair brush run across the design on the knife, thereby to bare the metal of the article to correspond with the design to be etched. The use of fusel-oil in the gum-guaiac varnish combines with the alkali printing composition in such manner, it is believed, as to assist in causing the second coating of varnish to recede from the design in the manner set forth. The design is then etched in the metal, Figs. 9 and 10, by the use of a suitable acid—as, for instance, nitric acid—combined with water in some suitable manner, after which the acid-resisting coating is removed, Figs. 11 and 12, and the knife polished or burnished in the usual way, and which polishing can then be done without appreciably affecting the quality of the design, which has heretofore been a difficult matter to accomplish. In practice I have found that, even with the additional time required to apply the second varnish or acid-resisting coating, a very much larger number of knives can be etched per day with this improved process, since comparatively little skill is required to do the work, than can be etched by the use of the process heretofore patented, since considerable skill and care were required in order to secure results which were much less perfect and desirable than those obtained by the use of this improved process.

As above set forth, owing to the fact that I am able to use a second varnish which more effectively resists the action of the acid I can use acid twice as strong as that used with other methods in vogue, and consequently the etching of the metal is much deeper, so that when the metal is burnished the design will not be appreciably affected.

Before the application of the acid the metal which has been bared by the washing out of the design may be dried in some suitable manner, if desired, whereby on the application of the acid such acid will not be neutralized by the water remaining on the metal and which was used to wash out the design.

Having thus described my invention, what I claim is—

1. The process of etching designs in metal, which consists in first coating the metal with a material adapted to act as a base for the design; then printing the design on such coat; then flowing the metal with an acid-resisting material adapted to protect all parts of the metal except the design; and then etching such design in the metal.

2. The process of etching designs in metal, which consists in first coating the metal with a material adapted to act as a base for the design; then printing the design on such coat; then flowing the metal with an acid-resisting

material adapted to protect all parts of the metal except the design; then washing out such design to bare the metal corresponding therewith; and then etching the same.

5 3. The process of etching designs in metal, which consists in first coating the metal with a material adapted to act as a base for the design; then printing the design on such coat with a material adapted to combine with the 10 material of such coat; then flowing the metal with an acid-resisting material adapted to protect all parts of the metal except the design; then washing out such design to bare the metal corresponding therewith; and then 15 etching the same.

4. The process of etching designs in metal, which consists in coating the metal with a gum-guaiac varnish; then stamping the design therein by the use of an alkali composition; then protecting all parts of the metal except the design by an acid-resisting varnish; then washing out the design to bare the plate corresponding therewith; and then etching the design in the plate.

25 5. The process of etching designs in metal, which consists in coating the metal with a gum-guaiac varnish; then stamping the design thereon by the use of an alkali composition; then protecting all parts of the metal 30 except the design by an acid-resisting varnish comprising bitumen, rosin, and balsam-fir dissolved in turpentine and benzol; then washing out the design; and then etching the bared metal by the use of an acid.

35 6. The process of etching designs in metal, which consists in first coating the metal with a thin layer of varnish having an antidrier incorporated therein; then stamping thereon the design; then applying a protecting-coating to such article thereby to protect all parts thereof except the design; then washing out the design; and then etching the bared metal.

40 7. The process of etching designs in metal,

which consists in first coating the metal with a varnish having fusel-oil incorporated therein; then stamping thereon the design by the use of an alkali composition; then protecting all parts of the article except the design by a second varnish coating; then washing out the design; and then etching the bared 45 50 metal.

8. The process of etching designs in metal, which consists in first coating the metal with gum-guaiac varnish having fusel-oil incorporated therein; then stamping the design 55 thereon by the use of an alkali composition; then protecting all parts of the metal except the design by a second varnish coating; then washing out the design; and then etching the bared metal.

9. The process of etching designs in metal, which consists of applying thereto a coating of gum-guaiac varnish having fusel-oil incorporated therein; then stamping thereon the design by the application of a potash solution; then protecting the metal around such design by the application of a varnish coating comprising bitumen, rosin, and balsam-fir dissolved in turpentine and benzol; then 65 washing out such design; and then etching 70 the metal to correspond with such design.

10. The process of etching designs in metal, which consists in coating the metal with gum-guaiac varnish having fusel-oil incorporated therein; then stamping the design thereon 75 with an alkali solution; then protecting the metal around such design by a varnish consisting of bitumen, rosin, and balsam-fir dissolved in benzol and turpentine; then washing out such design; then drying the metal; 80 and then etching the metal to correspond with such design.
